United States Patent Office

Des. 185,314
Patented May 26, 1959

185,314

WASTE BASKET

Jean O. Reinecke, Oak Park, Ill., assignor to Federal Tool
Corporation, Chicago, Ill., a corporation of Illinois

Application February 6, 1958, Serial No. 49,529

Term of patent 14 years

(Cl. D58—4)

FIG. 2

FIG. 3

Fig. 1 is an elevational view of a waste basket embodying my new design;

Fig. 2 is a top plan view thereof; and

Fig. 3 is a bottom view of the waste basket.

I claim:

The ornamental design for a waste basket, substantially as shown.
